UNITED STATES PATENT OFFICE

CLYDE EDWARD PLOEGER, ALVIN E. BURGESS, AND WALTER A. KUENZLI, OF EVANSVILLE, INDIANA, ASSIGNORS TO SERVEL INC., OF NEW YORK, N. Y., A CORPORATION OF DELAWARE

MOTOR COMPRESSOR UNIT

Application filed January 30, 1931. Serial No. 512,312.

This invention relates to compressors and more particularly to motor-compressor units for use in mechanical refrigerating systems.

The invention is herein described in connection with an hermetically sealed motor-compressor unit for use in a refrigerating system of the compression type. It is desirable that a unit of this character be quiet in operation, compact and simple in structure, and adequately lubricated over a long period of time.

It is an object of the invention to provide a motor-compressor unit fulfilling the above requisites and which is highly efficient in operation.

Further objects and advantages will be apparent from the following description taken in connection with the accompanying drawings wherein

Fig. 1 is an elevation partly in vertical section showing an hermetically sealed motor-compressor unit contemplated by this invention;

Fig. 2, a detail section of the cross-head and yoke taken on line 2-2 of Fig. 1;

Fig. 3, a view similar to that of Fig. 1 but at right angles thereto;

Fig. 4, a detail section of the compressor and driving arrangement taken on the line 4-4 of Fig. 1;

Fig. 5, a detail section of the compressor valve plate taken on the line 5-5 of Fig. 1; and

Fig. 6, a longitudinal section through the vertically supported compressor exhaust muffler.

Referring to Fig. 1, a compressor 10 is driven by a vertical electric motor 11 through a crank 12 journaled in a cylindrical cross-head 13 reciprocable in a tubular yoke 14 to which the cylinder of the compressor 10 is attached. The compressor and the motor are mounted as a unit on a frame 18 supported by upstanding lugs 16 on the crank-case adapted to cooperate with and fit into recesses 17 in the frame 18, the recesses being lined with sound deadening material 19. A dome or cover 20 provided with heat radiating fins 21 is secured to the crank-case 15 by a retaining ring 50 or lugs 22 and bolts 23.

The electrical connections to the motor are made through the crank-case by means of fluid tight insulating bushings 24 of dielectric material. The joint between the crank-case 15 and the dome 20 is made fluid tight and the interior of the casing is exhausted of air and moisture and utilized as part of the low pressure side of the refrigerant circulation system, being connected to the evaporator through a conduit 25 which terminates with 60 in the casing at 26 as shown in Fig. 3.

The compressor, shown in detail in Fig. 4, includes a stationary piston 26 removably mounted in the frame extension 27 of the frame 18 and is held therein by the valve plate 31. In one end of the piston is mounted a check valve 28 which cooperates with a removable valve seat 26' for normally closing a passage 29 through the length of the piston, said valve being unseatable by the action of the compressor. The passage 29 communicates with the exhaust port 30 in a valve plate 31 which is also attached to the extension 27 of the motor frame. The compressor cylinder 32 cooperating with the piston 26 is attached to or made integral with a tubular yoke 14 and is provided with an intake port 33.

The vertical motor 11 is provided with a hollow shaft 34 having at its lower end an eccentric portion or crank 12 and a counter-balance 35. The crank 12 is journaled in the cross-head 13 which reciprocates in the tubular yoke 14. A passageway 36 in the cross-head 13 communicates at one end with an intake pipe 37 attached to the cross-head and extending into the chamber within the compressor casing and the other end of passage 36 cooperates with the yoke to open and close intake port 33 in a cylinder 32 responsive to the reciprocating movement of the cross-head in the yoke.

As shown in Fig. 5 the valve plate 31 is provided with a passage 38 communicating at one end with the compressor exhaust port 30 and opened and closed by a check valve 39. A passage 40 opening into the passage 38 between the exhaust port 30 and the check valve 39 is opened and closed to the interior of the sealed casing by valve 41 operated by 100

a magnetic device 42 responsive to the leakage flux of the electric motor as shown in Fig. 1. The purpose of the valve 41 is to equalize the pressures on both sides of the compressor piston until the motor comes up to operating speed at starting.

The exhaust passage 38 in the valve plate 31 communicates with the condenser connection 43 through check valve 39 and a muffler 44 as shown in Figs. 3 and 6. The muffler 44 comprises an enlarged chamber 45 baffled by a series of felt or other porous material disks 46 held in place by perforated metallic disks 47.

15 In order to afford lubrication for the moving parts of the motor-compressor there is provided a pump operated by the relative motion between the cross-head and yoke. As shown in Figs. 2 and 4 a cylindrical pump

20 chamber 48 in the cross-head 13 opens at one end at the bearing surface of the crank 12 and receives a piston 49 attached to an extension or bridge 50 over the end of the tubular yoke 14. It is not necessary that the 25 parts of the oil pump be arranged as shown, but the piston may be on the cross-head and the cylinder in the yoke, or any arrangement whereby the pump is operated by the relative motion in the cross-head and yoke drive.

30 Oil is drawn into the pump chamber 48 from the bottom of the crank-case 15 through a pipe 51 attached to the lower end of the eccentric crank 12 and communicating with intake valve opening 52 in the crank 12

35 through a passage 53. Oil is forced from the pump cylinder 48 through the outlet valve opening 54 and passage 55 in the eccentric crank 12 into the hollow motor shaft 34 from where it may be distributed to the motor bearing 40 in any desired manner as, for instance, through small radial ducts in the shaft.

In operation, gas is drawn into the compressor through pipe 37, passage 36 and intake port 33. An additional port 56 may be 45 provided in the cylinder 32 to insure a complete charge of gas before the start of the compression stroke. The compressed gas is discharged through check valve 28, passage 29, port 30, passage 38, check valve 39 and 50 muffler 44 into the line 43 which is adapted to be connected to the condenser in a refrigerating system. Sound of the gas discharge through valve 39 is muffled by the smoothing action on the gas flow of the felt disks 46 in 55 the muffler 44.

It will be obvious to those skilled in the art that various other changes may be made in the construction and arrangement without departing from the spirit of the invention and therefore the invention is not limited to what is shown in the drawings and described in the specification but only as indicated in the appended claims.

We claim:

65 1. A motor-compressor unit including a

casing, a frame supported within said casing, a compressor mounted on said frame and comprising a stationary piston and a reciprocable cylinder, a motor also mounted on said frame and having a hollow shaft with ducts leading from the interior of the shaft to the motor bearing surfaces, a yoke attached to the compressor cylinder, a cross-head reciprocable in said yoke and having a valve opening adapted to cooperate with the compressor intake port, a pump comprising a cylinder formed in the cross-head and a piston attached to the yoke, a crank on the motor shaft journaled in the cross-head and having intake and discharge valve openings for said pump, the discharge opening communicating with the interior of the motor shaft and the intake opening communicating with an intake pipe connected to the crank.

2. A motor-compressor unit including an hermetically sealed casing, a frame supported within said casing, a compressor mounted on said frame and comprising a stationary piston and a reciprocable cylinder, a vertical motor also mounted on said frame and having a hollow shaft with radial ducts leading from the interior of the shaft to the motor bearing surfaces, a tubular yoke attached to the compressor cylinder, a cylindrical cross-head reciprocable in said yoke and having a valve opening adapted to cooperate with the compressor intake port, a pump comprising a cylinder formed in the cross-head and a piston attached to the yoke, a crank on the motor shaft journaled in the cross-head and having intake and discharge valve openings for said pump, the discharge opening communicating with the interior of the motor shaft, and the intake opening communicating with an intake pipe connected to the crank.

3. A motor-compressor unit including an hermetically sealed casing, a frame supported within said casing, a compressor mounted on said frame and comprising a stationary piston and a reciprocable cylinder, a vertical motor also mounted on said frame and having a hollow shaft with radial ducts leading from the interior of the shaft to the motor bearing surfaces, a tubular yoke attached to the compressor cylinder, a cylindrical cross-head reciprocable in said yoke and having a valve opening adapted to cooperate with the compressor intake port, a pump comprising a cylinder formed in the cross-head and a piston attached to the yoke, a crank on the motor shaft journaled in the cross-head and having intake and discharge valve openings for said pump, the discharge opening communicating with the interior of the motor shaft and the intake opening communicating with an intake pipe connected to the crank, a muffler in the discharge line of the compressor, and an unloader valve for said compressor.

4. A motor-compressor unit including a

casing, a vapor intake line communicating with the chamber enclosed by said casing, a frame removably mounted within said casing, noise deadening supports for said frame, 5 a motor mounted on said frame, a compressor also mounted on said frame, a yoke and cross-head drive between the motor and the compressor and a pump operated by the relative movement in said drive, the cross-head having a passage adapted to cooperate with the 10 intake port of the compressor.

5. A motor-compressor unit including a casing, a vapor intake line communicating with the chamber enclosed by said casing, a 15 frame removably mounted within said casing, noise deadening supports for said frame, a motor mounted on said frame, a compressor also mounted on said frame, a yoke and cross-head drive between the motor and the compressor, a pump operated by the relative 20 movement in said drive, the cross-head having a passage adapted to cooperate with the intake port of the compressor and a muffler in the discharge line of said compressor.

25 6. In a motor-compressor unit, a yoke and cross-head drive between the motor and compressor, and a lubricant pump operated by the relative motion in said drive, the cross-head having a passage adapted to cooperate 30 with the compressor intake port.

35 7. The combination of a crank, reciprocating pumps located at right angles to each other and arranged to be operated by said crank, a cross-head rotatably mounted on said crank, a yoke slidably mounted on said cross-head, valve passages in said crank for controlling the admission and discharge of fluid to one 40 of said pumps, and a valve passage in said cross-head for controlling the admission of fluid to another of said pumps.

45 8. In combination, a reciprocating compressor, a yoke integral with the movable element of said compressor, a cross-head adapted to reciprocate in said yoke, a pump chamber in said cross-head, and a piston adapted to reciprocate in said pump chamber and connected to said yoke.

50 9. A motor-compressor unit comprising a reciprocating compressor, a counter-balanced crank, a motor for driving said crank, a cross-head and yoke drive between said crank and said compressor, a pump adapted to be operated by the relative motion in the cross-head and yoke drive, a fluid tight casing around 55 said motor and compressor, an inlet port for said pump communicating with the lower portion of the chamber enclosed by said casing, and an outlet port for said pump communicating with passages which lead to the 60 moving parts of said motor-compressor.

65 10. In a motor driven reciprocating mechanism, a yoke and cross-head drive between the motor and reciprocating mechanism, and 70 cooperating pump elements constituted by

75 portions of said cross-head and said yoke and driven by the reciprocatory motion of the cross-head with respect to the yoke.

70 11. In combination, a reciprocatory mechanism, a driving motor for said mechanism having a crank, a yoke and cross-head drive between the crank and said mechanism, and an oil pump driven by the reciprocatory motion of the cross-head with respect to the yoke, said crank having intake and discharge 75 valve openings for the oil pump.

75 12. The combination of a crank, a reciprocating compressor, a cross-head and yoke drive between said crank and said compressor, and an oil pump driven by the relative movement of the cross-head with respect to the yoke, said crank having intake and discharge valve passages for said oil pump and the cross-head having a passage adapted to cooperate with the intake port of said compressor.

80 In testimony whereof we affix our signatures.
